S. GEORGE.
BELT BUCKLE.
APPLICATION FILED AUG. 9, 1916.

1,230,886.

Patented June 26, 1917.

UNITED STATES PATENT OFFICE.

SAFE GEORGE, OF HATTIESBURG, MISSISSIPPI.

BELT-BUCKLE.

1,230,886.

Specification of Letters Patent. Patented June 26, 1917.

Application filed August 9, 1916. Serial No. 114,023.

To all whom it may concern:

Be it known that I, SAFE GEORGE, a citizen of Syria, residing at Hattiesburg, in the county of Forrest and State of Mississippi, 5 have invented new and useful Improvements in Belt-Buckles, of which the following is a specification.

This invention relates to improvements in the construction of belt buckles.

10 The primary object of the invention is to produce a belt buckle which will effectively grip at the belt to hold the same adjusted upon the buckle.

Another object of the invention is to produce a belt buckle, primarily adapted for men's use having a finger thereon to engage in the loop at the front of the trousers, or to be received in the flap at the said front of the trousers and being further provided 20 with gripping means to engage with the shirt to prevent the shirt from riding upwardly.

It is a still further object of the invention to produce an article of this class which 25 shall embody the desirable features of simplicity, cheapness and thorough efficiency.

With the above and other objects in view the improvement resides in the construction, combination and arrangement of parts set 30 forth in the following specification and falling within the scope of the appended claims.

In the drawing:

Figure 1 is a perspective view of the belt buckle constructed in accordance with the 35 present invention,

Fig. 2 is a longitudinal sectional view through the same showing the belt connected with the buckle and the free end of the belt engaged by the buckle,

40 Fig. 3 is a view illustrating the application of the belt buckle, parts being broken away and parts being shown in section.

Fig. 4 is a rear elevation of the device,

Fig. 5 is a similar view but illustrating a 45 modification in the clamp and finger,

Fig. 6 is a detail perspective view of the form of clamp illustrated in Fig. 5, and

Fig. 7 is a detail perspective view of a 50 still further modified form of clamp.

55 The buckle is broadly indicated by the character A and preferably comprises a substantially rectangular member having spaced substantially elongated slots 1 and 2 divided by a central partition 3. The partition 3 may be provided with a rearwardly extend-

ing portion of bendable material which is adapted to be bent over the rear of the partition and have its end inturned and formed with teeth 4 which are adapted to be forced into engagement with one of the ends of 60 the belt 5.

The longitudinal edges provided by the slot, 1, at the partition 3, may be extended inwardly or the buckle may be otherwise formed with inwardly extending spaced 65 lugs 6, the said lugs each having an alining opening to receive the lugs 7 provided upon the tongue 8 of the buckle. The tongue is constructed from a flat piece of metal and has its outer end widened whereby to contact with the outer face of the buckle on the opposite sides of the slot 1, and the said tongue terminates a slight but suitable distance from the outer wall provided by the said slot 1. 75

The buckle A at the lower edge thereof is formed with an inturned longitudinally extending finger 9, and this finger is adapted to be received in the loop ordinarily provided for the tongue of the ordinary buckles 80 upon trousers, or the said loop may be received in the flap at the front of the trousers.

The buckle upon the rear face thereof has hingedly secured to its upper edge, as at 10, a clamp member 11. This clamp member comprises two spring jaws 12 and 13 respectively, the jaw 12 having its lower edge provided with a transverse depression 14 and one of the walls provided by the said depression is serrated to provide teeth 90 15. The second jaw 13 has its lower edge turned inwardly toward the jaw 11, as at 16, and the edge of this portion 16 is serrated to provide teeth 17, the said teeth being received in the grooves of the other jaw and 95 these teeth are adapted to engage with the shirt of the wearer whereby to sustain the shirt below the waistband of the trousers.

The strap or belt 5 is first passed through the opening 1 and the tongue swung to engage with the same after the proper adjustment of the belt has been made. Thereafter the free end of the buckle is passed through the slot 2, and each of the parts communicating with the said slot 2 is preferably provided with teeth 18 which engage with and sustain the said buckle in the said slot. 100 105

In Fig. 5 the buckle A at the lower edge thereof and adjacent one of the ends of the same is provided with a depending eye mem- 110

ber 20 through which passes a rod 21 that has both of its ends provided with heads 22-22. This rod may be employed in lieu of the finger previously described, and as 5 the said rod is longitudinally adjustable with relation to the buckle, the finger may be readily arranged to be brought to engagement for the purpose previously described. Also in Fig. 5 I have illustrated a 10 slightly modified form of clamp which is also illustrated in detail in Fig. 6 of the drawings. The clamp is hingedly connected with the buckle and comprises a pair of spaced angularly disposed arms 23-23, the 15 said arms having their ends turned inwardly, as at 24 and 25, to provide the same with spring jaws and the arm 24 has its upper edge rounded upon itself, as at 26, whereby the material may be compressed 20 between the jaw 25 and the arm 23 to which it is connected.

In Fig. 7 I have illustrated a still further modified form of the clamp. This clamp is also adapted to be hingedly connected with the buckle and includes an arm 25 27 that has its end, at one of its edges, provided with right angularly extending jaw members 28 and 29 respectively, the lower jaw member 27 being slightly offset from 30 but in a parallel line to the jaw member 28.

Having thus described the invention, what I claim is:

1. A buckle having upon its rear face a hinged clamp, comprising two spring jaws which exert a tension toward each other. 35

2. A buckle having its inner face provided with a hinged clamp comprising two spring jaws each exerting a tension toward the other, one of said jaws having its lower end formed with a transverse depression 40 and being provided with teeth, the lower edge of the other jaw having an inturned portion to be received in the depression of the first mentioned jaw. 40

3. A belt buckle comprising a plate having two elongated openings and a partition dividing the openings, a hook upon the lower edge of the buckle, a spring clamp upon the inner face of the buckle, a tongue having one of its ends pivotally secured in 50 one of the openings, said tongue comprising a flat plate one of the ends of which being widened to contact with the outer face of the buckle, the partition being provided with teeth disposed beyond the second opening, and a bendable member also provided with teeth upon the partition, as and for the purpose set forth. 55

In testimony whereof I affix my signature.
SAFE GEORGE.
